UNITED STATES PATENT OFFICE.

FREDRIK LJUNGSTRÖM, OF BREVIK, LIDINGON, AND ISIDOR BROBERG, OF SKARSATRA, LIDINGON, SWEDEN, ASSIGNEES TO AKTIEBOLAGET LJUNGSTRÖMS, ANGTURBIN, OF STOCKHOLM, SWEDEN, A CORPORATION.

LOCOMOTIVE PROVIDED WITH CONDENSER.

Application filed August 29, 1922. Serial No. 585,096.

To all whom it may concern:

Be it known that we, FREDRIK LJUNGSTRÖM, a subject of the King of Sweden, residing at Brevik, Lidington, Sweden, and ISIDOR BROBERG, a subject of the King of Sweden, residing at Tallhyddan, Skarsatra, Lidington, Sweden, have invented a new and useful Locomotive Provided with Condensers, of which the following is a specification.

10 This invention relates to locomotives provided with condensers and in which the movement is transmitted from a steam engine to a driving wheel device by means of a toothed gearing. The invention consists 15 chiefly in that the steam engine, the toothed gearing and the driving wheel device are located on a common bogie.

In case the steam engine in this manner is located on a bogie and consequently movable in relation to the condenser, it has proved difficult to conduct the waste steam of the steam engine to the condenser or to an accumulating liquid receptacle connected with the same or any other condensing receptacle. A further object of the invention consists in a movable steam connection between the steam engine, as for instance a steam turbine, and the condenser. Such a connection is preferably effected by the outlet of the steam engine, said outlet extending preferably into the condensing receptacle, being provided with a device connecting the outlet with the coupling of the condensing receptacle and yielding to all the movements of the bogie in relation to the receptacle. A further object of the invention consists in the steam outlet piping extending parallel or nearly parallel to the plane through the driving wheel shafts and into

40 the receptacle to a point situated right above or nearly right above the point of rotation of the bogie relatively to the receptacle, the turbine being preferably situated outside the end wall of the condensing receptacle and 45 the steam outlet being situated in the longitudinal direction of the condenser.

The invention is illustrated in the accompanying drawing in which—

Fig. 1 shows a locomotive consisting of 50 two carriages and having the driving machinery placed on a bogie pertaining to the condenser carriage. Fig. 2 illustrates an embodiment of a spherically movable cou-

pling device. Fig. 3 shows another embodiment of such a device.

Referring to Fig. 1, 1 designates the fore carriage supporting the steam boiler 2, the coal bunker 3 and the driver's cab 4. The rear carriage 5 supports the air cooled condenser 6, the liquid receptacle 7 and the driving aggregate 8 resting on the bogie 9. In the embodiment shown the driving aggregate consists of the turbine 11, the toothed gearing 12 and the connecting rod device 13. The steam turbine 11 is positioned at the one end of the receptacle 7 outside the end wall 14 of the receptacle, the steam outlet 15 of the turbine extending into the condensing receptacle 7 and being surrounded by a casing 16 connected with the condensing receptacle 7 or integral with the same. The outlet pipe 15 is parallel or nearly parallel to a plane through the driving wheel shafts and is connected with the casing 16 approximately above the point 65 of rotation 17 of the bogie relatively to the receptacle by means of a revolvable coupling 18. In order that the steam shall exhaust above the water contained in the liquid receptacle, the outlet pipe 15 is extended by a 70 bent pipe 19 fixed to the condensing receptacle. By the aid of this coupling between the turbine outlet 15 and the condensing receptacle 7 the turbine will be able to follow 75 all the movements of the bogie 9 about the point of rotation 17, which movements may be universal and caused on the one hand by the swinging movements of the bogie beneath the carriage and on the other hand by the springy movements of the carriage 80 on the bogie.

The driving means including a turbine may comprise any steam engine and be located in any other place near the liquid receptacle. It has, however, proved most suitable to place the aggregate outside the end wall of the condensing receptacle and the aggregate may also be situated on another carriage coupled to the condenser carriage by means of a coupling having a certain axis 95 of rotation. Also in this case the coupling device between the outlet of the turbine and the condensing receptacle may be constructed according to the invention by the articulated or elastic connection being placed in 100 or near the point of rotation.

- In Fig. 2, 15 designates the outlet of the turbine and 14 the end wall of the condensing receptacle forming a casing 16 surrounding the outlet 15. Near the line A—A the extension of which passes through the point of rotation mentioned above the steam conduit 15 is connected with the condensing receptacle or its casing 16 by means of a spherical coupling consisting of a part 23 situated on the pipe 15 and having an outer spherical surface co-operating with spherical surfaces 24 and 25 provided on the casing 16 or its accessory parts and packings 26 and 27. Located between the packings 26 and 27 is a recess into which water or steam is introduced through the pipe 28 thus increasing the tightness of the coupling. The packings may be tightened in usual manner by tightening the part 25.
- In the modified embodiment of the coupling device between the outlet 15 and the condenser 14 or its casing 16, shown in Fig. 3, the outlet is provided in the proximity of line B—B, the extension of which passes through the point of rotation mentioned above, with diaphragms 30 or is formed as such diaphragms, which owing to their elasticity may assume different positions thus allowing the mentioned movement of the outlet 15.
- Several embodiments of the invention may be imagined without deviating from its principle, since movable packings of any kind may be used.
- What we claim as new and desire to secure by Letters Patent of the United States of America is:—
1. In locomotives provided with condensers and in which the power is transmitted

from a steam engine to a wheel driving device by means of a toothed gearing, the waste steam supplied to the condenser passing into a condensing receptacle, an arrangement characterized by the steam engine, the toothed gearing and the wheel driving device being located on a common bogie, the outlet of the steam engine being yieldingly connected to said condensing receptacle so as to compensate for all movements of the bogie relatively to said receptacle. 40

2. An arrangement according to claim 1 characterized by the steam outlet being substantially parallel to a plane through the driving wheel shafts. 45

3. An arrangement according to claim 1 characterized by the steam outlet extending into the condensing receptacle to a point situated substantially right above the point of rotation of the bogie in relation to the condensing receptacle. 55

4. An arrangement according to claim 1 characterized by the steam outlet being coupled to the condenser by means of a spherical coupling device tightened by means of steam or water. 60

5. An arrangement according to claim 1 characterized by the steam engine being situated at the end wall of the condensing receptacle and having its outlet extending in the longitudinal direction of the condensing 70 receptacle.

In witness whereof we have hereunto set our hands in the presence of two witnesses.

FREDRIK LJUNGSTRÖM.
ISIDOR BROBERG.
